UNITED STATES PATENT OFFICE.

JOHN M. RIEDEL AND FERDINAND F. METZGER, OF PHILADELPHIA,
PENNSYLVANIA.

DESIGN FOR A MATCH-BOX.

SPECIFICATION forming part of Design No. 29,091, dated July 26, 1898.

Application filed June 28, 1898. Serial No. 684,695. Term of patent 7 years.

To all whom it may concern:

Be it known that we, JOHN M. RIEDEL and FERDINAND F. METZGER, citizens of the United States, residing in the city and county of Philadelphia, State of Pennsylvania, have invented and produced a new and original Design for Match-Boxes, of which the following is a specification, reference being had to the accompanying drawings, forming part 10 thereof.

The leading feature of our design for a match-box is a body and bottom of the form of a cartridge elliptical in cross-section.

Figure 1 represents a perspective view of 15 a match-box embodying our design. Fig. 2 represents a section thereof on line *x-x*, Fig. 1.

In the drawings, A designates the body of the box, and B designates the bottom thereof. The body and bottom in side elevation simulate the form of a cartridge, but in cross-section are elliptical. 20

C designates the lid of the box.

Having thus described our invention, what we claim as new, and desire to secure by Letters Patent, is—

25 The design for a match-box, substantially as shown and described.

JOHN M. RIEDEL.

FERDINAND F. METZGER.
